TOY BATSMAN

Application filed July 5, 1928. Serial No. 290,510.

This invention relates to improvements in amusement devices, of the type employed in simulated ball games, commonly used for entertainments and the like.

5 The primary object of this invention is to provide a figure toy of the above mentioned character adapted to add to the attractiveness of a simulated ball game.

A further object of this invention is to 10 provide a device of the above mentioned character, which may be operated by a child and does not require mechanical skill for operation as do most mechanical toys of this character.

15 A still further object of this invention is to provide a device of the above mentioned character adapted to be easy in operation and construction and comprising comparatively few parts.

20 Other objects and advantages of the invention will be apparent during the course of the following description.

In the accompanying drawings forming a 25 part of this specification and in which like numerals are employed to designate like parts throughout the same:

Figure 1 is a side elevational view of this invention, showing the parts in assembled position.

30 Figure 2 is a cross sectional view taken on line 2—2 of Figure 1 showing the operating mechanism inclosed in the pedestal.

Figure 3 is a vertical cross sectional view 35 taken on line 3—3 of Figure 1 showing fragmentary cross sections of the figure toy and of the base or pedestal support.

Figure 4 is a fragmentary cross sectional view taken on line 4—4 of Figure 1 showing the ball feeding mechanism employed in this 40 invention.

Figure 5 is a cross sectional view taken on line 5—5 of Figure 1 showing the mechanism installed in the body portion of the figure toy for causing the rotation thereof.

45 In the drawings, wherein for the purpose of illustration is shown, a preferred embodiment of the invention, the numeral 6 indicates a pedestal support in the form of a box like structure having a top 7 and a bottom 8 and corresponding sides and ends for spac-

ing the top 7 from the bottom 8, thereby forming means for inclosing suitable operating mechanism which will be fully described in due order.

A figure toy including a trunk portion 9 and a body portion 10 is secured to the top 7 of the box structure 6. The trunk portion 9 may be secured to the top 7 by any well known method. Arms 11 are secured to the body portion 10 and a miniature baseball bat 12 is secured in the hands of the arms 11.

A bearing 13 is secured in place in the upper portion of the trunk 9 while a corresponding bearing 14 is secured in the upper portion of the figure toy 10. The bearings 13 and 14 are adapted to receive a vertical shaft 15 which passes through the bearing 13 and which is secured to the bearing plate 14. In this manner the body portion 10 of the figure toy may be rotatably mounted in respect to 55 the trunk portion 9 of the figure toy to cause the baseball bat 12 to describe an arc during operation.

A coil spring 16 is adapted to have one of its ends 17 secured to the bearing plate 14 while its opposite end 18 is secured to the bearing plate 13 of the trunk portion 9. The coil spring 16 is assembled in 60 respect to the rotary body portion 10 so that when the baseball bat 12 is in the position shown in Figure 1, the coil spring 16 will be 65 70

fully unwound.

Any suitable means may be provided for partially rotating and tripping the vertical shaft 15 such as a disc 19 having openings 20 for receiving a series of teeth on a 65

gear wheel 21. The gear wheel 21 is secured to a shaft 22 having a handle 23 formed on the outer end and a cam 24 secured thereto, the operation of which will be 70

described in due course. The inner end of 75 the shaft 22 is supported by an extension 25 of the bracket 26 which also acts as a support for a stub shaft 27, upon which the disc 19 is mounted and secured in place. A lug 80

28 is formed on the lateral edge of the disc 19 for engaging an extension 29 of the vertical shaft 15. The mechanism described 85

thus far when operated causes the body portion 10 of the figure toy to be partially rotated in a clockwise direction and when the 90

95 figure toy is rotated in a counter-clockwise direction the disc 19 will be rotated in a clockwise direction and when the 100

lug 28 is rotated in the direction of the arrow shown in Figure 2, it causes the extension 29 to engage a trip 30 having a cam face 31 which raises the extension arm 29 out of engagement of the lug 28, thereby releasing the arm extension 29 therefrom.

A ball feeding mechanism is provided including a hollow shaft 32 having a hopper 33 formed on the upper end thereof for holding balls 34. The hollow shaft 32 is secured to the top 7 of the box structure and is placed in spaced relation from the figure toy including the front portion 9 and rotatable body portion 10. Loosely mounted to reciprocate in the hollow shaft 32 is a reciprocating rod 35 having bent portions at its upper end 36 forming a support for the balls 34, while the lower end 37 of the reciprocating rod 32 is bi-furcated to receive the cam 24 which is mounted on the operating shaft 22. The hopper 33 has its lower opening communicating with the hollow vertical shaft 32 so that the balls may drop upon the support 36 and be raised in position to be batted by the baseball bat 12. When the reciprocating rod 35 is raised by the cam 24 to its limit, the upper portion 36 of the reciprocating rod 35 is prevented from being flush with the upper edges of the vertical hollow shaft 32 in order that the balls 34 may engage the same and be held in position thereon.

For a consideration of the operation of this invention the operator may rotate the handle 23 in a clockwise direction which causes the vertical shaft 15 to be also operated in a clockwise direction. The vertical shaft 15 upon which the body portion 10 is secured is rotated in this manner causing the body portion 10 to be rotated in a clockwise direction under tension of the coil spring 16. After the body portion 10 has been thus rotated by the operating shaft 22, the cam 24 raises the reciprocating rod 35 in order to bring a ball 34 into striking position. As the cam 24 reaches this position the arm extension 29 will have been tripped by the trip 30 thereby disengaging the arm extension 29 from the lug 28 causing the coil spring 16 to rotate the body portion 10 in a counter-clockwise direction. The miniature baseball bat 12 will then strike the ball 34 a hard blow and cause the ball to travel through the air and at an object at which it is aimed.

It is to be understood that the form of the invention herewith shown and described, is to be taken as a preferred example of the same and that various changes in the size, shape and arrangement of parts may be resorted to without departing from the spirit of the invention, or the scope of the subjoined claims.

Having thus described our invention, we claim:

1. In a device of the character described,

a box like support, a figure toy mounted thereon, having its upper portion rotatable in respect to the body portion, a striking member carried by the rotatable body portion, a coil spring having one of its ends secured to the rotatable body portion and its opposite end secured to the trunk portion, a vertical rotary shaft passing through the trunk portion and having its upper end secured to the rotatable body portion, an angle arm formed on the lower end of the vertical rotary shaft, manual means for rotating the angle arm, a trip secured to the box like structure for disengaging the angle arm from the manual means causing the body portion to be rotated counter-clockwise, and a support carried by the box like structure for supporting a ball in the path of the striking member.

2. In a device of the character described, a box like support, a figure toy mounted thereon, having its upper portion rotatable in respect to the body portion, a striking member carried by the rotatable body portion, a coil spring having one of its ends secured to the rotatable body portion, and its opposite end secured to the trunk portion, a vertical rotary shaft passing through the trunk portion, and having its upper end secured to the rotatable body portion, an angle arm formed on the lower end of the vertical rotary shaft, manual means for rotating the angle arm including a support carried by the top of the box like structure, a shaft supported in the support, an operating handle formed on one end of the shaft, a gear mounted on the opposite end of the shaft, a rotary disc rotatably supported by the support, having openings adapted to be engaged by the gear teeth of the gear, a lug formed on the rotatable disc, a trip secured to the top of the box like structure mounted in the path of the angle arm for disengaging the angle arm from the lug formed on the rotary disc, thereby causing the rotatable body portion to be rotated in a counter-clockwise direction, and means for automatically feeding balls into the path of the striking member.

3. In a device of the character described, a box like support, a figure toy mounted thereon, having its upper body portion rotatable in respect to the trunk portion, a striking member carried by the rotatable body portion, a coil spring having one of its ends secured to the rotatable body portion, and its opposite end secured to the trunk portion, a vertical rotary shaft passing through the trunk portion, and having its upper end secured to the rotatable body portion, an angle arm formed on the lower end of the vertical rotary shaft, manual means for rotating the angle arm, including a support carried by the top of the box like structure a horizontal rotary shaft, having one of its ends supported by the support, an operating handle formed on one end of the horizontal rotary shaft, a gear

wheel secured to the opposite end of the horizontal rotary shaft, a rotary disc rotatably supported by the support, having openings adapted to be engaged by corresponding gear teeth of the gear, a lug formed on the rotatable disc adapted to engage the angle arm extension, a trip secured to the top of the box like structure mounted in the path of the angle arm for disengaging the angle arm from the lug formed on the rotary disc, thereby causing the rotatable body portion to be rotated in a counter-clockwise direction, and means for automatically feeding balls into the path of the striking member, said means including a vertical hollow shaft secured to the top of the box like structure in spaced relation from the figure toy, a hopper secured to the upper portion of the vertical hollow shaft, and having its lower opening communicating therewith, a reciprocating bar mounted to reciprocate in the vertical hollow support, said reciprocating rod having its lower end bi-furcated to receive the above mentioned cam secured to the horizontal rotary shaft, and said reciprocating rod having its upper end bent at right angles to form a support upon which the balls are adapted to rest.

In testimony whereof we affix our signatures.

MAX LEVIN.
JOHN R. LOPEZ.
